UNITED STATES PATENT OFFICE.

HERMAN G. HAASE, OF MINNEAPOLIS, MINNESOTA, ASSIGNEE OF ONE-HALF TO
ALEXANDER N. LIDELL AND ONE-HALF TO HENRY SLETTEN, BOTH OF MINNE-
APOLIS, MINNESOTA.

DEVICE FOR SINKING FOUNDATION-TUBES.

1,175,952.

Specification of Letters Patent.

Patented Mar. 21, 1916.

Application filed September 4, 1914. Serial No. 860,180.

To all whom it may concern:

Be it known that I, HERMAN G. HAASE, a citizen of the United States, residing at Minneapolis, in the county of Hennepin and State of Minnesota, have invented certain new and useful Improvements in Devices for Sinking Foundation-Tubes; and I do hereby declare the following to be a full, clear, and exact description of the invention, such as will enable others skilled in the art to which it appertains to make and use the same.

My invention relates to means for sinking foundation tubes, and is particularly directed to the improvement of the boring apparatus of the character disclosed and claimed in application of Henry Sletten and Alexander N. Lidell, filed June 12th, 1914, Serial Number 844,670, and entitled, "Device for sinking foundation tubes".

Generally stated, the invention consists of the novel devices and combinations hereinafter described and defined in the claims.

The apparatus disclosed in the said Sletten and Lidell application above identified, is adapted to bore and sink foundation tubes through sand and other comparatively soft earth, but is not well adapted for boring through very hard earth, or earth containing rock, and could not be used to bore through solid rock.

My invention is designed as a modification of the boring apparatus of the said Sletten and Lidell application and has in view the objections above noted.

In the accompanying drawings which illustrate the invention, like characters indicate like parts throughout the several views.

Referring to the drawings: Figure 1 is a vertical section illustrating a boring apparatus designed to cut through rock or through soil more or less laden with rock; Fig. 2 is a plan view of the parts shown in Fig. 1; and Fig. 3 is a detail in vertical section showing certain parts of the boring apparatus illustrated in Figs. 1 and 2.

The foundation tube is indicated by the numeral 1. The boring tool which is arranged to bore a hole larger than the diameter of the tube, is of novel construction, and comprises an upright shaft 10^a that is journaled in a suitable bearing on the boring frame 14, that is rigidly secured within

and to the lower section of the foundation tube 1. A worm gear 20 is secured to the upper end of the shaft 10^a and is adapted to be driven by a motor and other connections, preferably applied on the frame 14. The worm gear 20 meshes with a worm 19 driven by a gear 18, which, in turn, meshes with a pinion 17 carried by the armature shaft 16 of the electric motor 15. The said parts 15, 16, 17, 18 and 19 are diagrammatically indicated in Fig. 1, and they are journaled in suitable bearings afforded by an extended portion of the frame 14. So far as this invention is concerned, however, the shaft 10^a may be rotated by any suitable means. The shaft 10^a is provided with a depending rectangular portion that works through the angular bore of a hub 45, the flange of which is rigidly secured to a retaining collar 46. The angular portion of the shaft 10^a also depends into, but is free from a tubular supplemental bearing shaft 47 having a flanged upper end that is swiveled in the retaining collar 46. At its lower end, the supplemental bearing shaft 47 is provided with radial arms 48. Drilling tools or chisels 49 are pivoted to the outer ends of the arms 48, and drilling tools or chisels 50 secured to and depending from the intermediate portions of said arms. When the boring shaft 10^a is rotated, the head 45 will also be positively rotated, and the supplemental shaft 47 and arms 48 will also be caused to rotate by frictional engagement between the same and the retaining collar 46, but the movement thereof will not be positive and there will be more or less slippage, one way or the other, so that the chisels will not exactly repeat operations on successive rotations.

Under the above noted rotation of the supplemental shaft 47 and arms 48, they will be intermittently raised and then violently thrust downward by means of the following device. Surrounding the shaft 47 and compressed between one of the transverse bars of the frame 14 and a collar 51 on the said shaft 47, is a heavy coiled spring 52. Fixed on the said frame 14 and loosely surrounding the shaft 47 is a collar 53 having one or more cam lugs 54 for cooperative engagement with cam lugs 55 secured to and carried by the said supplemental shaft 47.

In the construction above described, when

the worm 20 and shaft 10^a are rotated, the arms 47 and the chisels or excavating tools carried thereby will be rotated and repeatedly raised by the cams 54-55 and then 5 released and violently thrust downward by the spring 52. The repetition of these actions will cause the excavating tool to work its way through hard pan clay, gravel, or even rock. The loosened materials will be 10 taken up, elevated and carried away by the conveyer 22-23, which conveyer is the same conveyer used in connection with the construction above described.

What I claim is:

- 15 1. The combination with a foundation tube, of a framework secured within the same, a rotary boring tool supported by said frame and working below said tube, mechanical devices serving to positively 20 raise and lower said boring tool under rotation thereof, and a motor having connections for positively rotating said boring tool.
2. The combination with a foundation 25 tube, of a framework secured within and to

the lower portion thereof, a boring tool supported by said frame and working below said tube, a spring for thrusting said boring tool downward, coöperating cams for intermittently raising and releasing said 30 boring tool under rotation thereof, and a motor on said frame having connections for rotating said boring tool.

3. The combination with the foundation tube, of a boring frame detachably applied 35 to the lower portion thereof, a motor on said frame, a boring tool mounted on said frame and working below said tube, a spring yieldingly forcing said boring tool downward, cams for intermittently raising 40 and releasing said boring tool, and connections from said motor for rotating said boring tool.

In testimony whereof I affix my signature in presence of two witnesses.

HERMAN G. HAASE.
